CLAIM

The ornamental design for an adjustable trocar stabilizing collar, as shown and described.

DESCRIPTION

FIG. 1 is a perspective view of an adjustable trocar stabilizing collar showing our new design;

FIG. 2 is a rear perspective view thereof;

FIG. 3 is a front elevational view thereof;

FIG. 4 is a bottom plan view thereof;

FIG. 5 is a right side elevational view thereof;

FIG. 6 is a top plan view thereof;

FIG. 7 is a left side elevational view thereof;

FIG. 8 is a rear elevational view thereof; and,

FIG. 9 is a perspective view thereof, the broken line showing of a surgical trocar is for illustrative purposes only and forms no part of the claimed design.
